FASTENER-FEEDING MECHANISM FOR BUTTON-ATTACHING MACHINES.

1,109,098.

Specification of Letters Patent.

Patented Sept. 1, 1914.

Application filed December 5, 1913. Serial No. 804,934.

To all whom it may concern:

Be it known that I, FRANKLIN R. WHITE, a citizen of the United States, and a resident of Watertown, in the county of Litchfield and State of Connecticut, have made and invented certain new and useful Improvements in Fastener-Feeding Mechanism for Button-Attaching Machines, of which the following is a specification.

10 My invention relates to fastener feeding mechanism for use with button attaching machines of the type wherein buttons are secured to a garment by means of a suitable fastener by upsetting, riveting or similar operation, and the object thereof is to provide certain improvements in and relating to the fastener feeding mechanism of button attaching machines of the type above referred to, and certain improvements in various of 15 the elements of said mechanism, all as hereinafter specifically referred to and described and finally claimed.

The drawings accompanying and forming a part of this application illustrate the preferred embodiment of my invention, although it will be understood that the same may be embodied in other specific forms and that my invention includes such variations and modifications of the specific embodiment thereof illustrated as will be obvious to those skilled in the art to which my invention relates.

In the accompanying drawings: Figure 1 is a view showing a portion of a button attaching machine in side elevation, the same being equipped with my improved fastener feeding mechanism; Fig. 2 is a view showing the same parts in front elevation; Fig. 3 is a view showing the principal parts of my improved fastener feeding mechanism upon a larger scale than the scale used in Figs. 1 and 2; Fig. 4 is a view similar to Fig. 3 but showing the parts shown in that figure in another position; Fig. 5 is a view showing a section taken upon a plane indicated by the line 5, 5, Fig. 3, looking in the direction indicated by the arrow; Fig. 6 is a fragmentary view showing a section upon a plane extending longitudinally of the chute along which the fasteners pass, and showing also a form of fastener which may be used; Fig. 7 is a similar view showing the parts shown in Fig. 6 in another position; Fig. 8 is a fragmentary view illustrating certain of the

elements of my improved fastener feeding mechanism; Fig. 9 is a fragmentary view illustrating a section taken upon a plane extending transverse to the fastener feeding chute; and Fig. 10 is a fragmentary view showing a section taken upon a plane indicated by the line 10, 10, Fig. 9, looking down.

Referring to the drawings wherein the preferred embodiment of my invention is illustrated, the reference numeral 12 designates a suitable support or pedestal, 13 a tray or table located at the upper end thereof, and 14 a suitable frame supported by the upper end of the pedestal and which frame serves to support the various operating elements of the button attaching machine hereinafter referred to and to which machine my improved fastener feeding mechanism is attached and of which it forms a part, the various elements being supported by the frame in proper relation with one another as will be understood.

Pivotedly supported by the frame 14 of the machine at the point 15 is an oscillating lever 16, one end of which is operatively connected with a vertically movable button setting plunger 17, while the other end is connected with a pitman 18 to which reciprocating motion is communicated from suitable operating mechanism and which pitman serves to communicate oscillatory motion to the lever 16.

Fig. 2 illustrates in a conventional manner a rotary button hopper 19 from which buttons are fed along a chute 20 to a button receiver 21 located immediately beneath the reciprocating plunger 17 hereinbefore referred to. The button setting plunger 17 is located directly over an anvil 22 to which fasteners are fed, as will hereinafter appear, and, as the plunger 17 is moved downward, it engages a button within the button receiver 21 and forces it downward until the projecting point or prong of the fastener enters the body of the button, after which said point is clinched by the lower end of the plunger in a manner well understood in button attaching machines.

The reference numeral 23 designates a rotary hopper designed to receive the fasteners whereby the buttons are secured to a garment and to feed them by the upper end of a downward extending fastener chute 24,

having overhanging sides as illustrated in the drawing to thereby hold the fasteners in place, and as is usual in fastener feeding mechanism. The lower end of said chute 5 terminates adjacent the anvil 22, and the fasteners, after they have been released from the lower end of the chute are moved onto the anvil upon which they rest with their point extending upward, as illustrated 10 in Fig. 5 of the drawing and as will be hereinafter explained in detail.

The reference numeral 25 designates an oscillating lever pivotally secured to the frame 14 of the machine at 26, and which 15 lever is provided with an elongated slot 27 in which a roller 28 carried by the oscillating lever 16 travels, whereby oscillatory motion is communicated to the said lever as will be understood. This oscillating lever is 20 provided with two arms 29, 30, the latter of which operates a fastener feeding slide as will be hereinafter shown, while the arm 29 is operatively connected with the inner end 25 of an oscillating lever 31, the outer end of which (see Fig. 2) is operatively connected with a pitman 31 which serves to communicate rotary motion to the hopper 23 through suitable ratchet mechanism designated as a 30 whole by the reference numeral 32, Fig. 1, but which mechanism is not illustrated in detail for the reason that it, as well as the hopper itself, form no part of the invention to which this application relates.

The reference numeral 33 designates a reciprocating stop designed to operate through 35 an opening 34 located in the bottom wall and adjacent the lower end of the fastener chute 24, and which stop arrests the downward movement of the fasteners in the chute when 40 the same is in its uppermost position, as illustrated in Fig. 6. This stop is shown as located at the free end of an oscillating member or lever 35, the other end of which is pivotally supported at 36 in lugs 37 formed upon the under side of the chute 24. The stop 33 is moved in a direction to bring 45 it into position to arrest the downward movement of the fasteners in the chute by means of a spring 38, acting upon the member 35, and in a direction to release the fasteners by means of an oscillating operating member or arm 39 which engages a cam surface or shoulder 40 upon the member 35 and swings the same away from the 50 chute, as shown in Fig. 7, this movement being against the tension of the spring 38 as will be understood. The operating arm 39 is secured to the lower end of a short oscillating shaft 82 supported in a bearing 55 formed in a lug 41 projecting from the fastener chute 24, which shaft carries at its upper end a plate 42 which in turn is provided with a downward extending pin 43, it being understood that the plate 42 and 60 operating arm 39 are connected with one

another in a unitary manner and move in unison.

Oscillatory motion is communicated to the oscillating operating member or arm 39 and, consequently, to plate 42 through a pitman 44 as shown in Fig. 10, the upper end of this pitman being operatively connected with the oscillating lever 31 hereinbefore referred to and as best shown in Fig. 2. The upper end of this pitman is provided 75 with a slot 45 in which a pin 46 carried by the lever 31 moves, so that said last mentioned lever may partake of a considerable movement before the pin 46 comes into contact with the end of the slot 45 and before beginning to transmit motion to the pitman 44. The lower end of the pitman 44 is also provided with a slot as shown at 80 47 in which a pin 48 carried by the operating member or arm 39 moves. A spring 49 is also provided one end of which is secured to the pitman 44 while the other end is secured to the pin 48. It will therefore be appreciated, referring to Fig. 5, that motion is transmitted to the operating member or arm 39 through the spring in the normal 85 operation of the machine, and that if for any reason the fastener feeding mechanism become jammed so that the operating member or arm 39 and the parts connected with it may not operate, as sometimes occurs by the fasteners becoming jammed in the feeding chute, the spring 49 will yield, thus permitting the pitman 44 to move independently of the pin 48.

The reference numeral 50 designates a second oscillating member pivotally secured at its upper end to a lug 51 projecting from the side of the fastener feeding chute 24 by means of a screw or equivalent pivot 52, and the lower end of which member is provided with a hook shaped projection 53 adapted to be moved into the path of the fasteners as shown in Fig. 4, or out of said path so as to be free of the fasteners, as shown in Fig. 3. This member is provided with a laterally projecting arm 54 at its upper end which arm is engaged by one end of a spring 55, the other end thereof being secured to a fixed abutment and the tendency of which spring is to move the member 50 into the position shown in Fig. 3 and to hold it normally in that position. The projection 53 at the opposite end of the member 50 is provided with a beveled or inclined face 83 adapted to contact with the fastener in the chute immediately below it when said projection 53 moves into and across the path of the fasteners, the object being to positively force or push the fastener below it and insure the movement of the fastener in case it be stopped or otherwise held against movement in the chute.

The oscillating member 50 above referred to is provided with an inclined cam surface 130

or shoulder 56 intermediate its ends which shoulder is engaged by the pin 43 projecting downwardly from the plate 42, as hereinbefore explained. The plate 42 is preferably made to overlie the oscillating member 50, as shown in Fig. 3, and upon rotary motion being imparted to the plate through the shaft 40, as above explained, the pin 43 engages the shoulder 56 and forces the lower hook-shaped projection 53 of said member toward the right, referring to Figs. 3 and 4, this movement being against the tension of the spring 55 as will be understood. The lower side of the projection 53 is inclined, as shown at 56, which inclined surface engages the prong of the lowermost fastener after it has been released by downward movement of the stop 33 and thereby gives the fastener a positive push as it passes from the lower end of the chute 24 as above described.

When the stop 33 is in the position shown in Fig. 6 the oscillating member 50 is in the position shown in Fig. 3. If now the oscillating operating arm 39 be moved in a downward direction, Fig. 10, through the pitman 44 and spring 49 as hereinbefore explained, the oscillating member 50 is moved from the position shown in Fig. 6 to the position shown in Fig. 7, and the stop 33 thereby moved out of the path of movement of the fasteners. Simultaneously with this operation the plate 42 is oscillated through the shaft 40 and the pin 43 engages the shoulder 56 and moves the lower hook-shaped projection 53 of the oscillating member 50 from the position shown in Fig. 3 to the position shown in Fig. 4. This movement brings the projection 53 into the path of movement of the fasteners and the upper edge of said projection into position to engage and arrest the downward movement of the fasteners in the chute, as shown in Fig. 4, and, as the projection is moved across the lower end of the chute the fastener which was released upon the downward movement of the stop 33 is engaged by the lower inclined edge 56 of the projection and given a positive push toward the lower end of the fastener chute. As the operating member or arm 39 is moved from the position shown in Fig. 7 to the position shown in Figs. 6 and 10, the stop 33 is returned by the action of the spring 38 into a position to arrest the downward movement of the fasteners in the chute 24, and reaches the position shown in Fig. 6 about the time that the extremity of the projection 53 reached the position in which it is illustrated in Fig. 3 to which position said projection is returned by the spring 55.

The fasteners pass from the lower end of the chute 24 onto a receiving table 57 shown in Fig. 5 and indicated in a conventional manner in Figs. 6 and 7, the lower end of the chute being provided with a foot as

shown at 58, Figs. 3 and 4, which fits close to the table and forms one of two parallel guides between which the fasteners are moved from the lower end of the chute onto the anvil 22. The other of said guides is shown at 59, Figs. 3 and 4 the same being pivotally supported at 60 upon a block 61 which block is in turn supported upon a second block 62 secured to the frame of the machine. These guides are spaced apart from one another as above explained to thereby provide a slot 63 along which the fasteners pass to the anvil 22, and the guide 59 is pivotally supported in order that it may be swung away from the guide 58 to thereby expose the lower discharge end of the chute 24 and permit fasteners to be removed, should they become jammed at the lower end of the chute. The movable guide 59 is held in place by means of a pin 79 which extends through a hole in it and into the block 61 above referred to.

The fastener receiving table 57 is itself provided with a slot 80, and the reference character 64 designates a reciprocating slide 90 movable between the guides 58, 59 and the forward end of which is adapted to engage each separate fastener as it reaches the receiving table and force the same along the slot 63 and onto the upper end of the anvil 22, as will be understood from Fig. 5 of the drawing. This slide is provided with a downwardly extending arm 65 which in turn is connected with a reciprocating cross-head 66 movable in suitable guides provided for it in the block 61 hereinbefore referred to. This cross-head is provided with a downwardly extending pin 67 which in turn is engaged by the bifurcated free end of one arm 68 of a bell crank lever pivotally secured to the block 62 at 69, the other arm 70 of said lever being operatively connected with the arm 30 of the lever 25 hereinbefore referred to (see Fig. 1) through a pitman 71, whereby as the lever 25 is oscillated as hereinbefore explained reciprocatory motion is transmitted to the slide 64. The particular form of the connection intermediate the arm 30 of the lever 25 and the arm 70 of the bell crank lever is however not specifically illustrated, as the same forms no part of the invention to which this application relates.

The fasteners are moved by the slide 64 from the lower end of the chute 24 into a position between the upper ends of two jaws 72, 73, the lower ends of which jaws are pivotally supported by a vertically movable jaw carrying member 74 surrounding the anvil 22 and held in its uppermost position by means of a spring 75, the upper ends of these jaws being forced toward one another by a spring 76. These jaws thus act to hold the fastener in an upright position with its head resting upon the anvil 22 after it has

been pushed thereupon by the slide 64, as illustrated in Fig. 5, in which position it remains until the button contained in the button receiver 21 is attached to the garment, as hereinbefore explained; it being understood that after the fastener has been supplied to the anvil the button contained within the button receiver is forced downward by the plunger 17 and through the button receiver and into engagement with the fastener, the upwardly projecting prong of which either pierces an imperforate bottom wall of the button, or passes through a hole provided therein; after which it is clenched within the hub of the button in a manner well understood by those familiar with the art relating to button attaching machines.

The pivoted guide 59 is provided with an upwardly extending wing or guard 77, and 20 78 designates a guard secured to the lower end of the fastener chute, the purpose of these elements being to prevent the garment from coming into engagement with the fastener releasing mechanism when the machine is in use, the guard 78 also assisting in holding the tack or fastener in its upright position when being forced downwardly by the inclined face 56 of the member 25 50 and avoiding any and all danger of it being forced out of the chute by the action of said member.

The oscillating lever 25 is so designed, and the location of the roller 28 is such that motion is communicated to said lever throughout the greater part of the upward movement of the connecting rod 18, from which it follows that the lever 31 which is operated from the lever 25 partakes of an oscillatory movement substantially in step with the movements of the levers 16 and 25. 35 The fastener feeding mechanism comprising in part the oscillating members 35 and 50, however, is operated only as the lever 31 approaches the ends of its movement because of the lost motion between said lever and the pitman 44, which lost motion results from the fact that the pin 46 moves in a slot 45 of considerable length, as hereinbefore explained. It therefore follows that the fastener feeding mechanism is operated and moved from the position shown in Fig. 3 to that shown in Fig. 4, and from the position shown in Fig. 4 to that shown in Fig. 3, very quickly, as these movements occur 50 55 while the lever 31 is moving through short portions only of its path of movement, which rapid operation of the fastener feeding mechanism is of importance, especially in fast running machines.

60 Having thus described and explained my invention, I claim and desire to secure by Letters Patent:

1. In a button attaching machine, fastener feeding mechanism comprising a downwardly extending chute along which fasten-

ers may pass; an oscillating member having a stop adapted to arrest downward movement of the fasteners in said chute; a second oscillating member independent of said first mentioned member and having a projection, and which second oscillating member swings in a plane substantially at right angles to the plane of movement of said first mentioned oscillating member; and operating mechanism adapted to simultaneously move said stop out of and said projection into the path of movement of the fasteners in said chute. 70 75

2. In a button attaching machine, fastener feeding mechanism comprising a downwardly extending chute along which fasteners may pass; an oscillating member supported by said chute and having a stop adapted to arrest downward movement of the fasteners; a second oscillating member independent of said first mentioned member and supported by said chute and having a projection, and which second oscillating member swings in a plane substantially at right angles to the plane of movement of said first mentioned oscillating member; and operating mechanism supported by said chute and adapted to simultaneously move said stop out of and said projection into the path of movement of the fasteners in said chute. 80 85 90 95

3. In a button attaching machine, fastener feeding mechanism comprising a downwardly inclined chute along which fasteners may pass; an oscillating member supported upon the under side of said chute and having a stop adapted to extend through an opening provided in the bottom wall of said chute and into a position to arrest downward movement of the fasteners; a second oscillating member independent of said first mentioned member and supported upon the upper side of said chute and having a projection; and operating mechanism supported by said chute and adapted to simultaneously move said stop out of and said projection into the path of movement of the fasteners in said chute. 100 105 110

4. In a button attaching machine, fastener feeding mechanism comprising a downwardly extending chute along which fasteners provided with body portions and with stems may pass; an oscillating member supported by said chute and having a longitudinal stop extending cross-wise of said chute and so located as to be engaged by the stems of said fasteners and thus adapted to arrest downward movement of the fasteners; a second oscillating member independent of said first mentioned member and supported by said chute and having a projection adapted to engage the body portions of said fasteners and thus arrest downward movement of the fasteners; an oscillating shaft; a bearing carried by said chute for support 115 120 125 130

- ing said shaft; and operating members connected with said shaft and adapted to operate said oscillating members.
5. In a button attaching machine, fastener feeding mechanism comprising a downwardly extending chute along which fasteners may pass; an oscillating member having a stop adapted to arrest downward movement of the fasteners; a spring acting upon said member and adapted to hold the stop thereof in the path of movement of the fasteners; a second oscillating member independent of said first mentioned member and having a projection adapted to arrest downward movement of the fasteners, and which second oscillating member swings in a plane substantially at right angles to the plane of movement of said first mentioned oscillating member; a spring acting upon 10 said member and adapted to hold the projection thereof out of the path of movement of the fasteners; and operating mechanism for moving said oscillating members in opposition to said springs.
- 25 6. In a button attaching machine, fastener feeding mechanism comprising a downwardly extending chute along which fasteners may pass; an oscillating member supported by said chute and having a stop adapted to arrest downward movement of the fasteners; a spring acting upon said member and adapted to hold the stop thereof in the path of movement of the fasteners; a second oscillating member independent of said first mentioned member and supported by said chute and having a projection adapted to arrest downward movement of the fasteners and which second oscillating member swings in a plane sub- 30 substantially at right angles to the plane of movement of said first mentioned oscillating member; a spring acting upon said member and adapted to hold the projection thereof out of the path of movement of the fasteners; an oscillating shaft; a bearing carried by said chute for supporting said shaft; and operating members connected with said shaft and adapted to move said oscillating members in opposition to said springs.
- 45 7. In a button attaching machine, fastener feeding mechanism comprising a downwardly extending chute along which fasteners may pass; an oscillating member having a longitudinally disposed stop extending cross-wise of said chute and thus adapted to arrest downward movement of the fasteners; a spring acting upon said member and adapted to hold the stop thereof in the path of movement of the fasteners; a second oscillating member independent of 50 said first mentioned member and having a projection adapted to arrest downward movement of the fasteners; a spring acting upon said member and adapted to hold the projection thereof out of the path of move- 55
- ment of the fasteners; an oscillating shaft; and operating means connected with said shaft and adapted to move said oscillating members in opposition to said springs.
8. In a button attaching machine, fastener feeding mechanism comprising a downwardly extending chute along which fasteners may pass; an oscillating member having a stop adapted to arrest downward movement of the fasteners; a spring acting 60 upon said member and adapted to hold the stop thereof in the path of movement of the fasteners; a second oscillating member independent of said first mentioned member and having a projection adapted to arrest downward movement of the fasteners; a spring acting 65 upon said member and adapted to hold the projection thereof out of the path of movement of the fasteners; an oscillating shaft; an arm secured to said shaft and one end of which is adapted to engage said first mentioned oscillating member and move it against the action of the spring acting thereupon; and operating means connected with said shaft and adapted to engage said second mentioned oscillating member and move it against the action of the spring acting thereupon.
9. In a button attaching machine, fastener feeding mechanism comprising a downwardly extending chute along which fasteners may pass; two oscillating members independent of and movable in planes substantially at right angles to one another and each of which is provided with means for arresting downward movement of the fasteners; spring mechanism acting upon said oscillating members and adapted to normally hold them in definite positions; and operating mechanism for moving said oscillating members in opposition to said spring mechanism to bring the arresting means of said members alternately into the path of movement of the fasteners.
10. In a button attaching machine, fastener feeding mechanism comprising a downwardly extending chute along which fasteners may pass; two oscillating members independent of and movable in planes substantially at right angles to one another and carried by said chute and each of which is provided with means for arresting downward movement of the fasteners; two springs, one acting upon each of said oscillating members; and mechanism carried by said chute for moving said oscillating members in opposition to said springs to bring the arresting means of said members alternately into the path of movement of the fasteners.
11. In a button attaching machine, fastener feeding mechanism comprising a downwardly extending chute along which fasteners may pass; two oscillating members independent of one another and car- 120

ried by said chute, and each of which members is provided with means for arresting downward movement of the fasteners; two springs, one acting upon each of said oscillating members; a bearing carried by said chute; an oscillating shaft supported in said bearings, and operating members carried by said shaft and adapted to move said oscillating members in opposition to said springs to bring the arresting means of said members alternately into the path of movement of the fasteners.

12. In a button attaching machine, fastener feeding mechanism comprising a downwardly extending chute along which fasteners may pass; two oscillating members independent of one another and carried by said chute, and each of which members is provided with a cam surface and with means for arresting downward movement of the fasteners; two springs, one acting upon each of said oscillating members; a bearing carried by said chute; an oscillating shaft supported in said bearing; an arm carried by said shaft and adapted to engage the cam surface of one of said oscillating members; a plate carried by said shaft; and a pin carried by said plate and adapted to engage the cam surface of the other of said oscillating members.

13. In a button attaching machine, fastener feeding mechanism comprising a downwardly extending chute along which fasteners may pass; an oscillating member having a stop at its free end adapted to arrest downward movement of the fasteners, and a cam surface or shoulder; a spring acting upon said member and adapted to hold the stop thereof in the path of movement of the fasteners; a second oscillating member independent of said first mentioned member and having a projection adapted to arrest downward movement of the fastener, and a cam surface or shoulder; a spring acting upon said member and adapted to hold the projection thereof out of the path of movement of the fasteners; an oscillating shaft; an arm carried by said shaft and adapted to engage the cam surface of said first mentioned oscillating member; a plate carried by said shaft; and a pin carried by said plate and adapted to engage the cam surface of said second mentioned oscillating member.

14. In a button attaching machine, fastener feeding mechanism comprising a

downwardly extending chute, means for arresting downward movement of fasteners in said chute, and for releasing separate fasteners in succession; an oscillating lever; a pitman intermediate said lever and said releasing means; a spring carried by said pitman and operatively connected with said releasing means and through which spring motion is transmitted thereto; and a lost motion connection between said lever and pitman whereby the latter may move throughout a part of its path of movement without operating the pitman.

15. In a button attaching machine, fastener feeding mechanism comprising a downwardly extending chute; means for arresting downward movement of fasteners in said chute, and for releasing separate fasteners in succession; an oscillating lever; a pin carried by said lever; a pitman having a slot at its upper end in which said pin operates, and having also a slot at its lower end; a pin carried by said fastener feeding mechanism and operating in the last mentioned slot; and a spring carried by said lever, one end of which spring is connected with said last mentioned pin and through which spring motion is transmitted to said fastener feeding mechanism.

16. In a button attaching machine the combination with a chute, of a spring-actuated member pivoted at one end and provided on its opposite end with a projection adapted to travel across said chute, said projection being formed with a straight edge whereby to act as a stop for the fasteners in said chute, and also provided with an inclined edge whereby to contact with and move the fastener immediately below the same.

17. In a button attaching machine the combination with a chute adapted to contain and guard the button fasteners, of a spring-actuated member pivoted at one end and provided with a projection at its opposite end, said projection being formed with an inclined face, and a guard located on one side of said chute and below which said projection is adapted to move.

Signed at Waterbury, in the county of New Haven and State of Connecticut, this 22nd day of November, A. D. 1913.
